UNITED STATES PATENT OFFICE.

BURNHAM C. STICKNEY, OF ELIZABETH, NEW JERSEY, ASSIGNOR TO UNDERWOOD TYPEWRITER COMPANY, OF NEW YORK, N. Y., A CORPORATION OF DELAWARE.

TYPEWRITING-MACHINE.

1,357,195,

Specification of Letters Patent.

Patented Oct. 26, 1920.

Application filed February 1, 1919. Serial No. 274,399.

To all whom it may concern:

Be it known that I, BURNHAM C. STICKNEY, a citizen of the United States, residing in Elizabeth, in the county of Union and State of New Jersey, have invented certain new and useful Improvements in Type-writing-Machines, of which the following is a specification.

This invention relates to typewriting machines and is herein disclosed as applied to an Underwood standard typewriting machine, employing a well-known kind of fan-fold web for the reproduction of several copies of writing upon a given form. Except in certain types of typewriting machines, known as the fan-fold billing machines, the manipulation of carbon sheets necessary to make duplicate and triplicate copies has been extremely annoying. In machines of the last-mentioned type, the difficulty of repositioning the carbon sheets relatively to the work-sheets has been overcome by making the typewriter platen shiftable to permit the work-sheets and carbon sheets to be straightened out, with the result that it is comparatively easy to shift the carbon sheets while still remaining interleaved between the work-sheets.

According to the present invention, such shifting of the platen may be unnecessary. Moreover, the device is adapted to be applied to an ordinary typewriting machine, without involving such reconstruction of the carriage as is usually necessary in the machines of the fan-fold billing kind. To obtain these and other results, I have found it advantageous to provide a structure mounted in the usual platen frame of an Underwood typewriting machine and extending upward. In order to obtain straight stretches of webs for the repositioning of the carbon sheets relatively to the work-sheets, I have found it desirable to mount the carbon sheets upon rollers in the frame above the platen, and to provide guiding devices for separating the carbon sheets and the work-sheets, so that they may move relatively to each other without friction upon one another. By using rollers, the guiding devices may be much shorter than the length of carbon sheet utilized, and

may become practically mere devices for separating the carbon sheets from the web if desired.

The structure mounted upon the platen frame may comprise end brackets or devices in which the rollers carrying the carbon sheets are journaled, and may also comprise feed rolls for feeding the carbon sheets and the work-sheets together, said feed rolls being advantageously geared to the platen, so that they may serve not only for the repositioning of the work-sheets after being repositioned relatively to the carbon sheets, but may also serve for line-spacing and the other purposes of typewriting. If the platen is provided with the usual feed rolls, the usual casting off key may serve to release both the usual feed rolls and the feed rolls above the platen. After the work-sheets have been fed forward beyond the carbon sheet rollers, the work-sheets may be brought together, so as to be severed by a single operation of a knife and all may be positioned for severing by gaging against the end-gage.

If a fan-fold web is used, the guiding devices may comprise a slitting knife adapted to slit the web into its separate sheets in order to permit the web sheets to be separated to allow the carbon paper to be positioned relatively to them. The rollers that carry the carbon paper may be normally tensioned by springs tending to wind up the paper, but may be detained by ratchet pawls to enable the carbon sheets when unrolled to be held unrolled. Thus the carbon sheets and the webs may be so positioned as to permit them to be grasped between the aforementioned feed rolls, and to be fed rearwardly by said feed rolls down past the printing point.

Other features and advantages will hereinafter appear.

In the accompanying drawings,

Figure 1 is a face view, largely broken away, of an Underwood typewriter carriage having my invention applied thereto.

Fig. 1^a is a detail view, partly in section, showing the mounting of a carbon roll.

Fig. 2 is a perspective view of the web-slitting devices as seen from above.

Fig. 3 is a fragmentary, separated, perspective view of an upper feed roll and some associated mechanism.

Fig. 4 is a side view, showing the connections between the casting off means and the feed rolls.

Fig. 5 is a fragmentary, perspective view of a carbon sheet roller.

Fig. 6 is an end view, showing the ratchets for the carbon sheet rollers and a handle for releasing them.

Fig. 7 is an end view from the opposite side, showing stops for the carbon sheet rollers.

15 Fig. 8 is a sectional, side view of the parts seen in Fig. 1, with the feed rolls cast off and ready to have the sheets of the web severed.

20 Fig. 9 is a diagrammatic perspective view, showing the work-sheets at the beginning of writing on a form.

Fig. 10 is a similar view, showing the position at the end of writing on a form.

25 Fig. 11 is a view similar to Fig. 10, with the work-sheets further advanced to bring the carbon sheets clear of all the curves in the work-sheets to permit their readjustment relative thereto.

30 Fig. 12 is a perspective view, showing the parts adjusted as in Fig. 8.

Fig. 13 is a fragmentary, perspective view, largely broken away, of the guides for the work-sheets.

35 In the Underwood typewriting machine, a fan-fold web or plies of other work-sheet 20 are led from the rear of the platen frame 21, down over a paper-table 22, beneath a platen 23, the platen being journaled in ends 24 of the platen frame. In order to hold 40 the work-sheet against the platen and to cause it to advance at the operation of the usual line-space slide 25, which is effective through the usual pawl 26 upon the line-space wheel 27, there are provided rear feed 45 rolls 28 and front feed rolls 29, which are mounted in frames 30, journaled on a shaft 31 and adapted to be cast off by rotating the usual casting off shaft 32. For operating this casting off shaft, there is provided the 50 usual handle 33, which is connected by a link 34 to a rock arm 35 upon the shaft 32, so that when the handle is depressed, the flat cam faces 36 of the shaft 32 will spread rock arms 37 upon the frames 30 against the 55 tension of springs 38, which usually hold the rolls against the platen.

60 According to the present invention, there are provided feed rolls 39 and 40 above the platen, which may either take the place of the feed rolls 28 and 29 or may supplement them, and the feed rolls 39 and 40 may be adapted to feed forward the work-sheet 20, because the feed roll 40 is geared to the platen by an intermediate idle pinion 41, 65 meshing with a pinion 42 fast upon the

platen axle and with a pinion 43 fast upon the axle 44 of the feed roll 40, the pitch diameters of the pinions being so adjusted as to cause the feed roll 40 to feed the work-sheet 20 forward at the same rate as the 70 platen tends to turn it. The feed rolls 39 and 40 may be normally forced together by means of a spring 48, which bears against arms 45 and 46, upon which the feed rolls 39 and 40 are respectively journaled by 75 means of their axles 47 and 44.

Whenever it is desired to move the work-sheets relatively to the platen, the handle 33 may be shifted to cast off the rolls 39 and 40 from the work-sheet, thereby releasing 80 the work-sheet and at the same time casting off the feed rolls 28 and 29 if the latter are employed. To enable the feed rolls 39 and 40 to be thus cast off, the arms 45 and 46, which may be identical and support each 85 end of the feed roll axles or shafts 47 and 44, are journaled in stub shafts 49 fast upon brackets 50 and 51, which are held by screws to the usual top plates 52 and 53 of the platen frame, said stub shafts lying within 90 the platen frame 21.

The work-sheet 20 is herein shown as fan-folded and as comprising a front sheet or web 54, a second sheet or web 55, a third sheet or web 56 and a back sheet or web 57, 95 all fan-folded lengthwise and integral with the front sheet 54. When such fan-folded sheets are employed, they are preferably slit before they reach the feed rolls 39 and 40, and, for this purpose, there are provided a 100 series of sharp edged, pointed slitting knives 58 fast in a paper guiding frame 59, which is fast to the brackets 50 and 51.

The paper guiding frame 59 is herein disclosed as comprising a series of plates 60, 105 61, 62, 63 and 64, between which are adapted to be guided the thicknesses of webs 54, 55, 56 and 57, alternately with a front carbon sheet 65, a central carbon sheet 66 and a rear carbon sheet 67, said carbon sheets being respectively fast to rolls 68, 69 and 70. These rolls are journaled in the brackets 50 and 51 in a manner which will be hereinafter disclosed. The plates 60, 61, 62, 63 and 64, forming the paper or sheet-guiding 110 frame, with the exception of the outer plates, are advantageously straight, with the result that carbon sheets and work-sheets lying between them will lie perfectly straight, and thus slip over the plates and over each 120 other with little or no friction, thus permitting the carbon sheets, when lying in or above said sheet-guiding frame, to be shifted relatively to the work-sheets. The paper or sheet-guiding frame 59 extends down toward 125 the top front of the platen and slants rearwardly therefrom. In addition to the sheet-guiding frame just described, there are provided other guiding devices for the sheet including a front guide plate 71 and a rear 130

guide plate 72 adapted to carry the front web 54 and the rear web 57, respectively, away from the adjacent carbon sheets.

In setting up a new web or webs, as the case may be, and new carbons in the machine, as at the beginning of a day's work, the carbon sheet 65 is advantageously the first to be threaded into position. This may be done by rotating the carbon roll 68 backwardly while guiding the carbon sheet by inserting a finger through one of the front openings 73 in the guide plate 71. If desirable, or necessary, the typist may also insert a finger from the rear through openings 75 and 76 in the rear supporting guide plate 72, and in a V-shaped extension 78 of the guide plate 64.

To rotate the roll backwardly to unwind the carbon sheet, there is provided a handle 80 fast to the roll and projecting beyond the bracket 51. The typist rotates the roll backwardly by its handle 80 until the carbon sheet arrives at the lower edge of the guide 59, as shown in Figs. 8 and 12. There is a spring 81 normally tending to wind up the roll, but this spring is prevented from being effective at this time because a pawl 82 is pressed by a spring 83 against the ratchet wheel 84 fastened to the roll 68 by being fastened to an extension 85 of its axle.

When the carbon sheet has thus been properly positioned, the typist may position a stop 86 to render the pawl 82 unnecessary. To accomplish this, the stop 86 is formed as a member, comprising an arc edge 87 adapted to lie in a thread 88, said thread being adjustably fastened to the roll, and having an abutment or stop 89, so that the turning of the roll will be limited by the stop when the stop strikes the abutment 89 as the roll turns in one direction. For adjusting the thread and its abutment upon the roll, the axle 91 of the roll is journaled in an opening in the bracket 50 and is provided with a shoulder 92 bearing against the inner face of the bracket, so that the axle has a short extension 93 terminating in a shoulder 94, against which a sleeve 95 is adapted to bear, said sleeve having the thread 88 cut upon it. To adjust the sleeve 95 upon the axle 91, there is provided a thumb screw 96, which is adapted to be screwed down upon a threaded extension 97 of the axle 91, and, when so screwed down, holds the sleeve 95 jammed between the shoulder 92 and the thumb screw. When the carbon sheet 65 has been adjusted in the manner described, the sleeve is adjusted upon the carbon roll with the stop 86 against the stop 89, thus preventing any backward rotation of the roll after the pawl 82 is released from the ratchet 84.

After the first or front carbon sheet 65 has been thus adjusted, it will be usually found most convenient to adjust the second sheet 55 of the web 20, the web 20 having been previously slit into its sheets for this pur-

pose. The sheet 55 is carried up from between the guide plates 60 and 61 past the feed rolls 39 and 40, and the upper ends of these guide plates, and then is carried behind a roll extension 98 of the guide plate 70 71, and then in front of and over a roll extension 99 of a guide plate 100, which latter is adapted to hold the web clear of the roll 69. In order to facilitate the guiding of the web 55 over the guide plate 100, finger 75 openings 101 are provided in the guide plate. The web from the guide plate is carried upwardly through an opening 102 and past a knife 103, which is adapted to sever the webs at the opening, as will hereinafter appear.

The typist will next usually find it advantageous to thread the carbon sheet 66, which may be done in the same way as the carbon sheet 65 was threaded, except that the carbon sheet 66 passes between the guide plates 61 and 62 in the guide 59. Its bottom is alined with the bottom of the sheet 65. To enable it to be turned backwardly and controlled, its roller 69 is provided with a ratchet wheel 84, a pawl 82, a sleeve 95, a stop 86, and a thread 88, substantially like those provided for the roll 68, so that, when positioned, its pawl may be made unnecessary by the adjustment of its sleeve 95.

Next the typist will usually find it most convenient to thread the web-sheet 56 by carrying it up between the plates 62 and 63 of the guide 59, past the roll 70 and rearwardly over a curved guide 104, which is adapted to hold it clear of the carbon roll 70, and then behind the turned-over extension 105 of the plate 100, and thence upwardly through the opening 102 and past the knife 103.

The typist will next usually find it convenient to thread the carbon sheet 67. In doing this, the typist drops it downward by rotating its roll rearwardly and guiding it between the plates 63 and 64 of the guide 59, until its lower edge is in alinement with the other carbon sheets, in which position it is held by a pawl 82 like the above-described pawl 82. Its roll has a sleeve 95 adapted to be adjusted against its stop 89, so that the carbon sheet, like the other carbon sheets, will be held in position independently of its ratchet wheel and pawl.

Then the typist will find it convenient to thread the rear web-sheet 57 upwardly, carrying it in front of the feed roll 40, behind the V-shaped extension of the plate 64 and in front of the rear guide 72, the V-shaped plate 78 carrying it clear of the roll 70, so that the web 57 comes out of the opening 102 adjacent the knife 103. Finally, the typist, may thread the front web-sheet 54 in front of the guide plate 106, which forms the front plate of the guide 59. The typist carries the front web behind the feed roll 39,

- then over the guide 71, which holds it clear of the carbon roll 68, and thence carries it upwardly through the opening 102 and past the knife 103.
- 5 When the webs and carbon sheets have all been threaded in this manner, the typist may actuate a finger-piece 108 to swing the pawls 82 clear of their ratchet wheels 84. To accomplish this, each pawl may be in the form of a bell-crank having a tail 109, all of said tails overlying a circular extension 110 around the pivot 111 of the finger-piece 108, so that when the finger-piece 108 is swung, pins 112 upon said extension will 10 strike the tails of the pawls and carry the pawls clear of the ratchet wheels. The finger-piece 108 may be normally detained in its ineffective position by a spring 113, having a hollow 114, adapted to engage a pin 115 upon the finger-piece. When swung to effective position to release the pawls, an extension 116 of the spring may hold the finger-piece against a pin 117 adapted to limit its throw.
- 15 The typist may then swing the handle or finger-piece 33 to carry the feed rolls 39 and 40 against the platen, as well as the feed rolls 28 and 29, if the latter are provided. The connections, whereby the finger-piece 33 actuates the feed rolls 39, include a lug 118 upon the usual link 34, a link 119 being pivoted to said lug and also pivoted to an arm 120 of a rocking release frame 121. This release frame is pivoted upon the shafts 35 49 upon which the arms 45 and 46 are journaled, and when swung to releasing position, carries a pair of pins 123 and 124 against a pair of cam lugs 125 and 126 upon the arms 45 and 46, respectively, thus camming 40 the arms apart against the pressure of the strong spring 48. When the feed rolls 39 and 40 grip the work-sheets and the carbon sheets between them, the platen may be revolved backwardly by the usual handle 127 45 to bring the top writing line upon the outer web 54 to the printing point at the usual wing scale 128. The typist may then proceed to write by actuating the type keys and the usual line-space handle, thus alternately 50 writing and advancing the work-sheets until the form is filled out or the desired printed matter is written, which brings the carbon sheets to the position seen in Fig. 10.
- The typist then casts off the feed rolls 39 55 and 40 and either rotates the platen forwardly or draws upon the work-sheet-webs, which project from the opening 102, to bring the last writing line of the next form just above the lower end of the carbon sheets 65, 60 66 and 67. To enable this drawing of the web to be measured automatically, the brackets support an adjustable end gage 129 upon a gage arm 130, said gage arm being fast upon the top plate 131 carried by the brackets 65 50 and 51. When the webs have been thus gaged, the typist turns the finger-piece 33 to permit the spring 48 to throw the feed rolls 39 and 40 against the work-sheets, so that if the platen is now rotated backwardly, the work-sheets will draw the carbon sheets 65, 70 66 and 67 backwardly with them against the tension of the springs 81, which normally tend to wind up the carbon sheets upon their rollers. The typist rotates the platen backwardly until the first writing line upon the 75 outside web 54 is at the wing scales 128, and then proceeds to write upon the web and actuate the line-space handle as before.
- If the form or written out matter happens to be of the length from the opening 102 80 to the wing scale 128, the typist may actuate the knife 103 to sever the webs at the end of writing the second form, see Fig. 10, and then turn the platen forwardly to bring the carbon sheets to the Fig. 8 or 11 position, 85 and then release the feed rolls 39, as before, see Fig. 12, and gage the webs against the end gage 129. If the form is only a fraction of the length between the knife 103 and the wing scale 128, the typist may best delay the 90 severing until the requisite number of forms have been written to fill up this distance. Any fractional length of a form will be automatically taken care of by gaging the ends of the webs against the end gage 129, and 95 then severing by actuating the knife, care being taken to sever the webs immediately after the writing of a form and before the webs and carbon sheets reach the Fig. 12 position, since, if severed after gaging and 100 before being turned backwardly, the ends of the webs will fall below the knife and require rethreading. The knife 103 is advantageously pivoted on a bracket 135 projecting from the bracket 51, and is provided 105 with a handle 136 for actuating it. This enables the webs to be severed even though they are not held at the bottom by the feed rolls.
- In order to enable new rolls 68, 69 and 70, 110 carrying carbon paper, to be inserted, the extension 85 of each roll shaft may be journaled in a plate 137 fitting a corresponding opening in the bracket 51, and provided with a lug 138 through which a screw 139 115 is adapted to pass to hold the plate in position on the bracket. When the screw 139 is removed and the thumb screw 96 taken off, the roll may be withdrawn through the opening left by the removal of the plate 137. 120
- The object of having a screw-thread 88 to form the track between the stops 86 and 89 is to enable any desired number of rotations of the carbon-paper roll to be had without arresting the roll. In order to enable the 125 lug or stop 86 to travel in this thread, it is slidably mounted on a pin 140 fast in the bracket 50.
- It will be observed that the carbon sheets follow straight paths when they are clear 130

of the platen, and that the web-sheets follow curved paths. The guide plates 71, 72, 104, 100 and 105, may be so located that the distance each web travels from the feed 5 rolls 39 and 40 to the opening 102 is identical, with the result that when the knife severs one web at the desired point, it severs them all at the same point. If desired, the front plate 106 and the rear plate 64 may be 10 provided with flaring ends 145 and 146 to enable the carbon sheets to be more easily guided into the proper position. The feed rolls 39 and 40 advantageously work in openings 147 in the guide 59, which are considerably longer and wider than the rolls, thus 15 minimizing the distortion of the paper and the carbon sheets as they emerge from and enter between the plates 60, 61, 62, 63, 64, etc.

In order to make sure that the threaded 20 web-sheets 54, 55, 56 and 57 do not drop out of the opening 102, after being severed, the plate 131 may be provided with L-plates 141 and 142, having flaring flanges, between which the webs are guided, said L-plates 25 being held to the bottom of the plate by screws 143, one of said screws also passing through the bent-over bottom 144 of the end-gage arm 130, and thus serving to hold said arm in position. It will be observed 30 that if separate webs are used and the bottom feed rolls 28 and 29 are omitted, the top feed rolls 39 and 40 will feed both the front and the rear webs along a straight length, with the result that there will be no relative 35 creeping of the webs as they pass around the platen. This gives the present device a utility in connection with separate webs which is impossible to the same extent where feed rolls are depended upon which hold a 40 work-sheet against a curved surface, like the platen. The carbon rolls 68, 69 and 70 may be regarded as holding devices for carbon sheets, and the plates 106, 60, 61, 62, 63 and 64 may be regarded as separating devices 45 for separating the carbon sheets from the work-sheets, or as work-supporting devices. The plates 71, 100, 72, etc., also may be regarded as work-supporting devices for the webs or work-sheets, and the lugs or 50 stops 86 form devices for arresting the carbon sheets at the limit of their travel.

In order to facilitate the threading of the carbon sheets, the plates 106 and 64 may be flared out, as indicated at 145 and 146, thus 55 affording a large enough opening between them and the adjacent plates to readily thread the carbon sheet through. In order to facilitate the threading of the central carbon sheet, the plate 62 may extend higher 60 than the plate in front of it by a small amount, advantageously in the form of fingers, thus enabling the typist, when threading the central carbon sheet, to allow the carbon sheet to fall upon said fingers and be 65 guided by them down in between the plates,

If desired, similar fingers may be provided for assisting the threading of the work-sheets at the bottom of the lower ends of the plates 61 and 63.

Variations may be resorted to within the 70 scope of the invention, and portions of the improvements may be used without others.

Having thus described my invention, I claim:

1. In a typewriting machine, the combination with a platen, of a frame above the platen comprising devices for supporting work-sheets above the printing line upon the platen, separate devices for supporting carbon sheets, feed rolls above the printing 75 line on the platen, adapted to seize the work-sheets together with the carbon sheets to feed them to said devices, and means for driving the rolls at the same peripheral speed as the platen. 80

2. In a typewriting machine, the combination with a platen, of a frame above the platen comprising devices for supporting work-sheets above the platen, separate devices for supporting carbon sheets, feed 90 rolls above the printing line on the platen, adapted to seize the work-sheets together with the carbon sheets, means for driving the rolls at the same peripheral speed as the platen, bottom feed rolls adapted to hold 95 the work-sheets against the platen, and a single device for making all of said feed rolls simultaneously effective or ineffective.

3. In a typewriting machine, the combination with a platen, of a frame above the 100 platen, feed rolls above the printing line on the platen, a carbon-sheet-supporting device on the frame above said feed rolls, a work-sheet-supporting device also upon the frame, means for causing the carbon-sheet-supporting device to retract the carbon sheet upwardly between two work-sheets, and means for arresting the carbon sheet in position to be fed by the feed rolls. 105

4. In a typewriting machine, the combination with a platen, of a frame above the platen, feed rolls above the printing line on the platen, a carbon-sheet-supporting device on the frame, a work-sheet-supporting device also upon the frame, means for causing the carbon-sheet-supporting device to retract the carbon sheet between two work-sheets, means for arresting the carbon sheet in position to be fed by the feed rolls, and a finger-piece actuatable to release the feed rolls 110 to permit the carbon sheet to be readjusted relatively to the work-sheets. 115

5. In a typewriting machine, the combination with a platen, of a support for work-sheets and a carbon sheet above the platen, 120 devices for separating the work-sheets and the carbon sheet to enable the carbon sheet to be moved relatively to the work-sheets, and feed rolls on said devices adapted to cause all said sheets to be fed together. 125 130

6. In a typewriting machine, the combination with a platen, of a support for work-sheets and a carbon sheet above the platen, devices for separating the work-sheets and 5 the carbon sheet to enable the carbon sheet to be moved relatively to the work-sheets, feed rolls on said devices adapted to cause all said sheets to be fed together, other feed rolls adapted to hold the sheets against the 10 platen, and means for simultaneously making all said feed rolls effective or ineffective.

7. In a typewriting machine, the combination with a platen, of a support for work-sheets and a carbon sheet above the 15 platen, feed rolls above the platen, plates above and below said feed rolls to separate the carbon sheet from the work-sheets, means for casting off the feed rolls, and means for automatically moving the carbon 20 sheet relatively to the work-sheets when said feed rolls are cast off.

8. In a typewriting machine, the combination with a platen, of a support for work-sheets and a carbon sheet above the 25 platen, feed rolls above the platen, plates above and below said feed rolls to separate the carbon sheet from the work-sheets, means for casting off the feed rolls, means for automatically moving the carbon sheet 30 relatively to the work-sheets when said feed rolls are cast off, and connections whereby said feed rolls, when effective, drive the work-sheets at the peripheral speed of the platen.

35. 9. In a typewriting machine, the combination with a platen, of devices for carrying work-sheets and a carbon sheet around the platen, plates for separating the sheets along a straight stretch thereof, to enable 40 the carbon sheet to be moved relatively to the work-sheets, and feed rolls at one edge of said plates adapted to be made effective for seizing said sheets to feed the sheets together.

45. 10. In a typewriting machine, the combination with a platen, of devices for carrying work-sheets and a carbon sheet around the platen, plates for separating the sheets along a straight stretch thereof, to enable 50 the carbon sheet to be moved relatively to the work-sheets, feed rolls at one edge of said plates adapted to be made effective for seizing said sheets to feed the sheets together, means for causing said feed rolls to 55 turn at the same peripheral speed as the platen, and a finger-piece for making said feed rolls effective or ineffective, at will.

60. 11. In a typewriting machine, the combination with a platen, of devices for carrying work-sheets and a carbon sheet around the platen, plates for separating the sheets along a straight stretch thereof, to enable the carbon sheet to be moved relatively to the work-sheets, feeding devices for seizing 65 said sheets at one edge of said plates to

cause the sheets to feed together, and feed rolls adapted to hold the sheets against the platen to cause them to feed together when moved to the feed rolls by said feeding devices.

70

12. In a typewriting machine, the combination with a platen frame and a revolute platen therein, of ends for said frame, brackets mounted upon said ends, work-sheet-supporting devices mounted in said 75 brackets, adapted to guide work-sheets away from the platen, and carbon-sheet-holding rollers positioned between said work-sheets, adapted to automatically retract the carbon sheets from between the work-sheets, and 80 adapted to permit the carbon sheets to be retracted backwardly with the work-sheets around the platen.

85

13. In a typewriting machine, the combination with a platen frame and a revolute platen therein, of ends for said frame, brackets mounted upon said ends, work-sheet-supporting devices mounted in said 90 brackets, adapted to guide work-sheets away from the platen, carbon-sheet-holding rollers positioned between said work-sheets, adapted to automatically retract the carbon-sheets from between the work-sheets, and adapted to permit the carbon-sheets to be retracted backwardly with the work-sheets 95 around the platen, feed rolls journaled in said brackets above the platen, and pinions connecting said feed rolls to said platen to cause the work-sheets and the carbon-sheets to be moved backwardly when the platen is 100 turned backwardly.

100

14. In a typewriting machine, the combination with a platen frame and a revolute platen therein, of ends for said frame, brackets mounted upon said ends, work-sheet-supporting devices mounted in said 105 brackets, adapted to guide work-sheets away from the platen, carbon-sheet-holding rollers positioned between said work-sheets, adapted to automatically retract the carbon-sheets between the work-sheets, and adapted to permit the carbon-sheets to be retracted backwardly with the work-sheets around the platen, and plates for separating the work-sheets and the carbon-sheets, to permit the 110 carbon-sheets to be readjusted relatively to the work-sheets.

110

15. In a typewriting machine, the combination with a platen frame and a revolute platen therein, of ends for said frame, 120 brackets mounted upon said ends, work-sheet-supporting devices mounted in said brackets, adapted to guide work-sheets away from the platen, carbon-sheet-holding rollers positioned between said work-sheets, 125 adapted to automatically retract the carbon sheets between the work-sheets, and adapted to permit the carbon sheets to be retracted backwardly with the work-sheets around the platen, feed rolls journaled in 130

said brackets above the platen, pinions connecting said feed rolls to said platen to cause the work-sheets and the carbon sheets to be moved backwardly when the platen is turned 5 backwardly, and plates for separating the work-sheets and the carbon sheets, to permit the carbon sheets to be readjusted relatively to the work-sheets.

16. In a typewriting machine, the combination with a platen frame and a revoluble platen therein, of ends for said frame, brackets mounted upon said ends, work-sheet-supporting devices mounted in said brackets, adapted to guide work-sheets away 10 from the platen, carbon-sheet-holding rollers positioned between said work-sheets, adapted to automatically retract the carbon sheets between the work-sheets, and adapted to permit the carbon sheets to be retracted 15 backwardly with the work-sheets around the platen, and devices for adjustably limiting the turning of said rollers.

17. In a typewriting machine, the combination with a platen frame and a revoluble platen therein, of ends for said frame, brackets mounted upon said ends, work-sheet-supporting devices mounted in said brackets, adapted to guide work-sheets away 20 from the platen, carbon-sheet-holding rollers positioned between said work-sheets, adapted to automatically retract the carbon sheets between the work-sheets, and adapted to permit the carbon sheets to be retracted 25 backwardly with the work-sheets around the platen, plates for separating the work-sheets and the carbon sheets, to permit the carbon sheets to be readjusted relatively to the work-sheets, and devices for adjustably limiting the turning of said rollers.

18. In a typewriting machine, the combination with a platen frame and a revoluble platen therein, of ends for said frame, brackets mounted upon said ends, feed rollers journaled in said brackets, separating 30 devices for guiding work-sheets and carbon sheets to said feed rollers, devices for separately guiding the work-sheets outwardly from each other, and carbon-sheet-supporting devices positioned between the paths of the work-sheets.

19. In a typewriting machine, the combination with a platen frame and a revoluble platen therein, of ends for said frame, brackets mounted upon said ends, feed rollers journaled in said brackets, separating 35 devices for guiding work-sheets and carbon sheets to said feed rollers, devices for separately guiding the work-sheets outwardly from each other, carbon-sheet-supporting 40 devices positioned between the paths of the work-sheets, said work-sheets all having a path of the same length, means for bringing them together, and a knife for severing them at the point where they are brought 45 together.

20. In a typewriting machine, the combination with a platen frame and a revoluble platen therein, of ends for said frame, brackets mounted upon said ends, work-sheet-guiding devices above the platen, 50 mounted in said brackets, carbon sheet rollers also journaled in said brackets and comprising rolls of carbon sheets, ratchets for said rollers adapted to hold the rolls partly unrolled, springs normally tending to roll 55 up said rolls, stops for adjustably limiting the turning of said rollers, and means for making said ratchets ineffective.

21. In a typewriting machine, the combination with a platen frame and a revoluble 80 platen therein, of ends for said frame, brackets mounted upon said ends, work-sheet-guiding devices above the platen, mounted in said brackets, carbon sheet rollers also journaled in said brackets and comprising rolls of carbon sheets, ratchets for 85 said rollers adapted to hold the rolls partly unrolled, springs normally tending to roll up said rolls, stops for adjustably limiting the turning of said rollers, means for making 90 said ratchets ineffective, guiding and separating devices for the work-sheets and the carbon sheets, and feed rollers geared to said platen, adapted to feed the carbon sheets 95 and the work-sheets backwardly to the platen.

22. In a typewriting machine, the combination with a platen frame and a revoluble platen therein, of ends for said frame, brackets mounted upon said ends, work-sheet-guiding devices above the platen, mounted in said brackets, carbon sheet rollers also journaled in said brackets and comprising rolls of carbon sheets, ratchets for 100 said rollers adapted to hold the rolls partly unrolled, springs normally tending to roll up said rolls, stops for adjustably limiting the turning of said rollers, means for making 105 said ratchets ineffective, feed rollers for feeding the carbon sheets and the work-sheets together to the platen, and feed rollers adapted to hold the work-sheets against the platen.

23. In a typewriting machine, the combination with a platen frame and a revoluble 115 platen therein, of ends for said frame, brackets mounted upon said ends, work-sheet-guiding devices adapted to guide a front work-sheet forwardly and a rear worksheet rearwardly as they rise from the printing line upon the platen, a roller journaled between the paths of the work-sheets, adapted to hold a carbon sheet, and means for feeding the work-sheets independently 120 of their contact with the platen.

24. In a typewriting machine, the combination with a platen frame and a revoluble platen therein, of ends for said frame, brackets mounted upon said ends, work-sheet-guiding devices adapted to guide a 130

front work-sheet forwardly and a rear work-sheet rearwardly as they rise from the printing line upon the platen, a roller journaled between the paths of the work-sheets, 5 adapted to hold a carbon sheet, feed rollers for feeding said work-sheets and said carbon sheet independently of their contact with the platen, and separating devices for separating the carbon sheet and the work-sheets.

25. In a typewriting machine, the combination with a platen frame and a revoluble platen therein, of ends for said frame, brackets mounted upon said ends, a pair of 15 carbon sheet rollers journaled in said brackets, means for guiding a front work-sheet in front of one carbon sheet roller, means for guiding a rear work-sheet behind the other carbon sheet roller, means for guiding 20 a central work-sheet clear of both said rollers, and clear of the carbon sheets when once separated therefrom, and means for separating the carbon sheets and the work-sheets.

25. 26. In a typewriting machine, the combination with a platen frame and a revoluble platen therein, of ends for said frame, brackets mounted upon said ends, a pair of carbon sheet rollers journaled in said brackets, means for guiding a front work-sheet 30 in front of one carbon sheet roller, means for guiding a rear work-sheet behind the other carbon sheet roller, means for guiding a central work-sheet clear of both said 35 rollers, and clear of the carbon sheets when once separated therefrom, means for separating the carbon sheets and the work-sheets, and a pair of feed rollers for feeding the carbon sheets and the work-sheets backwardly to the platen.

27. In a typewriting machine, the combination with a platen frame and a revoluble platen therein, of ends for said frame, brackets mounted upon said ends, a pair of 45 carbon sheet rollers journaled in said brackets, means for guiding a front work-sheet in front of one carbon sheet roller, means for guiding a rear work-sheet behind the other carbon sheet roller, means for guiding 50 a central work-sheet clear of both said rollers, and clear of the carbon sheets when once separated therefrom, means for separating the carbon sheets and the work-sheets, a pair of feed rollers for feeding the carbon sheets and the work-sheets backwardly to the platen, and a pair of feed 55 rollers adapted to hold the work-sheets against the platen.

28. In a typewriting machine, the combination with a platen frame and a revoluble platen therein, of ends for said frame, brackets mounted upon said ends, a pair of carbon sheet rollers journaled in said brackets, means for guiding a front work-sheet 60 in front of one carbon sheet roller, means for

guiding a rear work-sheet behind the other carbon sheet roller, means for guiding a central work-sheet clear of both said rollers, and clear of the carbon sheets when once separated therefrom, means for separating 70 the carbon sheets and the work-sheets, a pair of feed rollers for feeding the carbon sheets and the work-sheets backwardly to the platen, and means for gearing said feed rollers to turn at the same peripheral speed 75 with the platen.

29. In a typewriting machine, the combination with a platen frame and a revoluble platen therein, of ends for said frame, brackets mounted upon said ends, a pair of 80 carbon sheet rollers journaled in said brackets, means for guiding a front work-sheet in front of one carbon sheet roller, means for guiding a rear work-sheet behind the other carbon sheet roller, means for guiding a central work-sheet clear of both said 85 rollers, and clear of the carbon sheets when once separated therefrom, means for separating the carbon sheets and the work-sheets, means normally tending to wind the carbon sheets on their rollers, and stops for adjustably limiting the turning of the rollers.

30. In a typewriting machine, the combination with a platen frame and a revoluble platen therein, of ends for said frame, brackets mounted upon said ends, a pair of carbon sheet rollers journaled in said brackets, means for guiding a front work-sheet in front of one carbon sheet roller, means for guiding a rear work-sheet behind the other 90 carbon sheet roller, means for guiding a central work-sheet clear of both said rollers, and clear of the carbon sheets when once separated therefrom, means for separating the carbon sheets and the work-sheets, means 95 normally tending to wind the carbon sheets on their rollers, stops for adjustably limiting the turning of the rollers, and ratchets for temporarily holding the rollers while the stops are being adjusted.

31. In a typewriting machine, the combination with a platen frame and a revoluble platen therein, of ends for said frame, brackets mounted upon said ends and extending above the platen, carbon sheet-supporting 110 devices adapted to move carbon sheets between the brackets, devices for separating work-sheets and carbon sheets, extensions of said devices for bringing the work-sheets together, a single knife for severing the 115 work-sheets when thus brought together, and a gage for gaging the length of work-sheet to be severed.

32. In a typewriting machine the combination with a platen frame and a revoluble 120 platen therein, of ends for said frame, brackets mounted upon said ends and extending above the platen, carbon-sheet-supporting 125 rollers journaled in said brackets, and normally tending to wind up the carbon sheets,

devices for separating work-sheets and carbon sheets, a knife for severing the work-sheets, and a gage for gaging the length of work-sheet to be severed.

- 5 33. In a typewriting machine, the combination with a platen frame and a revoluble platen therein, of ends for said frame, brackets mounted upon said ends and extending above the platen, carbon-sheet-supporting 70
10 rollers journaled in said brackets, means for guiding work-sheets in front of and behind and between said rollers, said means including guide-plates having openings adapted to admit the typist's fingers, and feed rolls 75
15 journaled in said brackets for feeding work-sheets and carbon sheets backwardly to the platen.

34. In a typewriting machine, the combination with a platen frame and a revoluble platen therein, of ends for said frame, brackets mounted upon said ends, carbon-sheet-supporting rollers journaled in said brackets, means for guiding work-sheets in front of and behind and between said rollers, said 80
20 means including guide-plates having openings adapted to admit the typist's fingers, feed rolls journaled in said brackets for feeding work-sheets and carbon sheets backwardly to the platen, and feed rolls adapted 85
25 to hold upon the platen work-sheets so fed.

35. In a typewriting machine, the combination with a platen frame and a revoluble platen therein, of ends for said frame, brackets mounted upon said ends, carbon-sheet-supporting rollers journaled in said brackets, means for guiding work-sheets in front of and behind and between said rollers, said means including guide-plates having openings adapted to admit the typist's fingers, 90
30 feed rolls journaled in said brackets for feeding work-sheets and carbon sheets backwardly to the platen, and gears for causing said feed rolls to drive the work-sheets with the same speed as the periphery of the 95
35 platen.

36. In a typewriting machine, the combination with a platen frame and a revoluble platen therein, of ends for said frame, brackets mounted upon said ends, a carbon sheet 100
40 roller journaled in said brackets, and a removable plate in one bracket adapted to permit the carbon sheet roller to be removed therethrough.

37. In a typewriting machine, the combination with a platen frame and a revoluble platen therein, of ends for said frame, brackets mounted upon said ends, a carbon sheet 105
45 roller journaled in said brackets, a removable plate in one bracket adapted to permit the carbon sheet roller to be removed therethrough, a spring normally tending to wind up said roller, anchored in said plate, and a ratchet wheel fast to the roller for controlling the spring.

65 38. In a typewriting machine, the combi-

nation with a platen frame and a revoluble platen therein, of ends for said frame, brackets mounted upon said ends, a carbon sheet roller journaled in said brackets, a removable plate in one bracket adapted to permit the carbon sheet roller to be removed therethrough, and a stop-sleeve adapted to be made fast to the opposite end of the roller, comprising a thread having abutments to limit the turning of the roller. 75

39. In a typewriting machine, the combination with a platen frame and a revoluble platen therein, of ends for said frame, brackets mounted upon said ends and extending above the platen, a pair of feed rollers, a pair of swinging brackets supporting each feed roller, and journaled in said first-mentioned brackets, a spring normally moving said feed rollers toward each other to seize work-sheets therebetween, and a finger- 80
45 piece for separating said feed rollers.

40. In a typewriting machine, the combination with a platen frame and a revoluble platen therein, of ends for said frame, brackets mounted upon said ends, work-sheet-guiding devices adapted to guide a front work-sheet forwardly and a rear work-sheet rearwardly, a roller journaled between the paths of the work-sheets, adapted to hold a carbon sheet, feed rollers for feeding said work-sheets and said carbon sheet, and separating devices in the form of plates having openings in which said rollers work for separating the carbon sheet and the work-sheets. 90
50

41. In a typewriting machine, the combination with a platen frame and a revoluble platen therein, of ends for said frame, brackets mounted upon said ends, work-sheet-guiding devices adapted to guide a front work-sheet forwardly and a rear work-sheet rearwardly, a roller journaled between the paths of the work-sheets, adapted to hold a carbon sheet, plates for separating said sheets, and feed rollers engaging said 100
60 sheets through openings in said plates.

42. In a typewriting machine, the combination with a platen frame and a revoluble platen therein, of ends for said frame, brackets mounted upon said ends, work-sheet-guiding devices adapted to guide a front work-sheet forwardly and a rear work-sheet rearwardly, a roller journaled between the paths of the work-sheets, adapted to hold a carbon sheet, plates for separating 110
70 said sheets, feed rollers engaging said sheets through openings in said plates, connections whereby said feed rollers turn at the peripheral speed of the platen, and means for making said feed rollers effective or ineffective, 115
80 at will.

43. In a typewriting machine, the combination with a platen, of a frame above the platen comprising devices for supporting work-sheets above the platen, separate de- 120
90

- vices for supporting carbon sheets, feed rolls above the printing line on the platen, adapted to seize the work-sheets together with the carbon sheets, means for driving the rolls 5 at the same peripheral speed as the platen, means for guiding the front and back work-sheets away from the central sheets on leaving said feed rolls, and plates between said rolls for separating intermediate sheets.
- 10 44. In a typewriting machine, the combination with a platen, of a frame above the platen comprising devices for supporting work-sheets above the platen, separate devices for supporting carbon sheets, feed rolls 15 above the printing line on the platen, adapted to seize the work-sheets together with the carbon sheets, means for guiding the front and back work-sheets away from the central sheets on leaving said feed rolls, and plates 20 between said rolls for separating intermediate sheets.
45. In a typewriting machine, the combination with a platen, of a support for fan-folded work-sheets and a carbon sheet above 25 the platen, devices for separating the work-sheets and the carbon sheet to enable the carbon sheet to be moved relatively to the work-sheets, feed rolls on said devices adapted to cause all said sheets to be fed together, 30 and slitting knives for separating the fan-folded sheet into its sheets.
46. In a typewriting machine, the combination with a platen, of a support for fan-folded work-sheets and a carbon sheet above 35 the platen, feed rolls above the platen, plates
- above and below said feed rolls to separate the carbon sheet from the work-sheets, means for casting off the feed rolls, means for automatically moving the carbon sheet relatively to the work-sheets when said feed 40 rolls are cast off, and knives adjacent said plates for slitting the fan-folded sheets into their separate sheets.
47. In a typewriting machine, the combination with a platen, of devices for carrying 45 fan-folded work-sheets and a carbon sheet around the platen, plates for separating the sheets along a straight stretch thereof, to enable the carbon sheet to be moved relatively to the work-sheets, feed rolls at one 50 edge of said plates adapted to be made effective for seizing said sheets to feed the sheets together, and knives adjacent said plates for slitting said fan-folded sheet into its separate sheets. 55
48. In a typewriting machine, the combination with a platen frame and a revolvable platen therein, of ends for said frame, brackets mounted upon said ends and extending above the platen, carbon-sheet-supporting devices adapted to move carbon sheets between the brackets, devices for separating work-sheets and carbon sheets, and knives at said devices for slitting a fan-folded sheet into separate work-sheets. 60
